UNITED STATES PATENT OFFICE.

WILLIAM W. WARNER, OF MIDDLETOWN, OHIO.

SKATER'S ARTICLE.

Application filed June 22, 1926. Serial No. 117,858.

This invention relates to articles of foot-wear and especially to articles of this kind which are adapted for use by skaters for the purpose of providing additional protection 5 against cold.

An object of my invention is to provide a protective covering for the upper part of the foot which may be conveniently worn over a shoe having a skate permanently attached thereto.

Another object is to provide a device for the purpose stated which is provided with means for snugly retaining it upon a skater's shoe and permitting freedom of movement.

15 These and other objects are attained by the means described herein and disclosed in the accompanying drawings, in which:

20 Fig. 1 is a side elevational view of a shoe carrying a permanently attached skate and having a device of my invention mounted thereon.

25 Fig. 2 is an inverted plan view of the device of my invention.

Fig. 3 is a view taken on line 3—3 of Fig. 1.

The protector of my invention is preferably made of hide or leather having the side carrying the wool, fleece, fur, or the like turned to the inside and the tanned face 30 turned outwardly and carrying the means for securing it upon a shoe. The device takes substantially the form of a shoe upper or buskin without a sole and may be conveniently formed of two substantially similar sides 5 and 50, secured together at the rear by a seam 6 and at the toe portion by stitching 7. Suitable reinforcing strips 8 and 9 are applied over the seams 6 and 7 at the rear and toe portions respectively. A 35 tongue 10 is provided in the protector and it also has its fleece or wool bearing side disposed inwardly and otherwise may be of any desired shape and secured upon the protector in any approved manner. The sides 5 and 50 have suitable reinforcing patches 11 which are disposed at that portion of the protector which fits over the narrow portion 40 of the shoe to which it is to be applied. A strap 12 is secured to one of the reinforcing patches or members and is adapted to be passed beneath the sole 13 of the skate shoe 14 and to be retained by a suitable securing element, such as a buckle 15 carried by the remaining reinforcing patch or member 11.

45 50 55 A toe securing means is provided by sewing or otherwise attaching a piece of leather or

other flexible material 16 to the bottom edge 17 of the side members 5 and 50 for a distance along the forward ends thereof. The member 16 is cut away centrally as at 18, so that the forward upright 19 of the shoe 60 skate 20 may be accommodated therein. A flap 21 is secured to the member 16 on one side of the opening 18 and carries on its free end a pair of snap fasteners 22, the complementary members 23 of which are carried by the member 16 on the opposite side of opening 18. Any suitable securing means 65 may be provided in lieu of the snap fasteners shown. By reference to Figs. 1 and 2 it 70 will be readily apparent that when the fasteners 22 and 23 and the strap 12 and buckle 15 are separated, the protector may be very readily placed over the skate shoe comprising the shoe 14 having the skate structure 20 permanently attached to the sole thereof, the slot or opening 18 permitting the toe securing member 16 to be passed about the upright 19 of the skate and permitting the flap 21 to be passed rearwardly thereof for securing the toe portion 15 in abutment with 75 the bottom of the sole 13 of the shoe. The strap 12 is then passed beneath the narrow portion of the sole 13 and secured by means of the buckle 15. By reference to Fig. 1 it 80 will be noted that the bottom edges 17 of the protector are drawn downwardly so that they completely cover the upper of the shoe but leave the edge of the sole 13 exposed. The purpose of securing the protector in this 85 manner is to permit substantially all of the side edges of the sole to receive the wear and rough usage incident to skating, and thereby to substantially eliminate tearing or fraying of the bottom portion of the protector. The 90 toe securing means 16 disposes the forward part of the protector in its proper and preferred relation to the sole of the shoe so that the wear at the toe portion is received by the relatively tougher material of the toe 100 piece 16.

The operation and use of the device is obvious. A skater desiring additional warmth for his feet may apply a pair of the protectors to the skate shoes and secure them in the proper relation to the sole of the shoe by means of the snap 21 and strap 12. The protectors may be readily opened by loosening or undoing the laces 25 which pass through the suitable eyelets 24 at the opening 26 of the protectors. This permits the protector to be opened so as to render ac- 105 110

cessible the normal shoe laces 27 for the skate shoe 14. When the skate shoe is laced and secured to the foot of a wearer, the fleece or wool bearing side of the tongue 10 is positioned over the laced portion of the skate shoe, after which the protectors are closed by tightening the laces 26 and thereby retaining the tongue 10 in position. In this way the entire upper of the skate shoe 14 is covered by the soft warm material while the sole 13 and the skate 20 are entirely free of impediment to use.

It will be noted that the fleece or wool which is disposed against the upper of the 15 skate shoe serves as a heat insulating medium so that the warmth of the wearer's foot is retained therein and that by securing the bottom edge of the protector closely about the sole 13 of the shoe 14, the escape of the heat 20 is precluded and the cold winds cannot find their way between the edge of the protector and the edge of the shoe sole. It will of course be understood that the devices of my invention may be applied with equal efficiency 25 and nicely over skates which are permanently attached to a skater's shoe and those which are attachable to ordinary shoes.

What I claim is:

1. As a new article of manufacture, a protector for skate shoes and the like having an inner face bearing a heat insulating material, and comprising a soleless upper provided with a continuous bottom edge, and securing means at the front and center portions of its bottom edges for retaining said bottom edges adjacent the sole of a skate shoe.
2. In a device of the class described, a bottomless upper of fleece lined material, a slotted toe securing member, means for substantially closing the slot in said member and a center strap for drawing the bottom edges of said upper toward one another.
3. In combination with a shoe having a skate permanently attached to the sole thereof, a removable protector comprising an auxiliary shoe upper having an open bottom adapted to cover the upper of the skate shoe and securing means adapted to pass beneath the sole of the skate shoe and about the skate for positioning the bottom edges of the protector along the top edge of the shoe sole.
4. In a device of the class described a re-

movable shoe upper having on its inside surface a fibrous heat insulating material, a slotted toe portion on the bottom of said upper, means for closing the slot in said toe portion and a strap and securing means therefor disposed forwardly of the heel portion of said upper.

5. As a new article of manufacture an auxiliary shoe upper for use upon skate shoes comprising an upper having a soft lining material, securing means adapted to be passed about the sole of the shoe forwardly of the heel and a second securing means closable over the toe of the shoe and about a portion of the skate.

6. A skater's article of footwear comprising a cold protective upper member having closable top opening and securing means for retaining the forward portion of said upper member about and substantially inclosing the forward end of a shoe.

7. A skater's article of footwear comprising a soleless cold protective upper to be worn over a skate shoe and having a toe securing means for embracing the forward end of said skate shoe and adjustable means for securing the lower edge of the upper about the top of the skate shoe sole.

8. In a skater's device the combination with a skate shoe having a depending skate member adjacent the toe portion thereof, of an auxiliary cold protective upper for mounting on the skate shoe and a toe securing means on said upper comprising a slotted toe member for receiving the depending skate member, and a closable flap on the toe member for precluding separation of the upper and the shoe and depending skate member.

9. The combination with a shoe and a skate associated therewith of a removable covering for the entire upper portion of the shoe and substantially free of the shoe sole and skate.

10. A skater's article comprising an upper adapted to completely cover the upper portion of a skater's shoe and having means at its forward end encasing the toe portion of the sole of said skater's shoe, said means being arranged to removably embrace the forward portion of a skate.

In testimony whereof, I have hereunto subscribed my name this 17th day of June, 1926.

WILLIAM W. WARNER.
